 Filed Nov. 16, 1964, Ser. No. 411,317
 Claims priority, application Spain Nov. 15, 1963
 3 Claims. (Cl. 129—1)

This invention relates to devices for filing and storage purposes and pertains in particular to such devices utilizing horizontal tensioned threads as the supporting means.

An object of this invention is to provide a device of the character described in which the threads are provided with attached pins cooperable with openings in the sheet to be filed so as to readily allow engagement of the sheets with the pins.

Another object of this invention is to provide an improved identifying device which may be easily attached to one of the threads.

The novel features that are considered characteristic of the invention are set forth with particularity in the appended claims. The invention itself, however, both as to its organization and its method of operation, together with additional objects and advantages thereof, will best be understood from the following description of specific embodiments when read in connection with the accompanying drawings, wherein like reference characters indicate like parts throughout the several figures and in which:

FIG. 1 is a side elevational view of the supporting framework;

FIG. 2 is a plan view of the assembly shown in FIG. 1 and illustrating the threads attached to the supporting framework;

FIG. 3 is a vertical section taken along the plane of section line I—I in FIG. 2 and showing the pin and sheet connection;

FIGS. 4 and 5 are enlarged views illustrating the manner of engaging a sheet with its pins;

FIG. 6 is a view similar to FIG. 3 but showing the manner of attaching an identifying card;

FIG. 7 is a view showing the upper portion of one of the sheets to be filed; and

FIG. 8 is a view showing one of the identifying cards illustrated in FIG. 6 and showing the disposition of the slits and holes.

As shown in FIGS. 1 and 2 the framework comprises a pair of spaced, parallel straps 6 each having an upstanding web 3 provided at one end thereof with an arcuate seat. The two straps are supported on a base each horizontally spaced as shown in FIG. 2 and are anchored to the base by suitable means such as screws. The aforementioned arcuate seats at the ends of webs 3 support a rod or bar 1, each strap 6 being provided at its opposite end with an upstanding flange through which the bolt members 5 are passed and which also pass through a second bar 2 and are threadedly engaged therewith so that rotation of the bolts 5 will move the bar 2 toward and away from the bar 1 as desired.

The two parallel bars 1 and 2 serve to support a plurality of threads or filaments 8 each of which is anchored at its opposite ends to the respective bars 1 and 2 by means of the C-shaped rings 7. In this fashion, it is possible to remove the threads from their supports without dismounting the framework or moving the bars 1 and 2.

Each thread 8 carries a plurality of pins 9 in spaced relationship to each other as is shown most clearly in FIGS. 3 and 6.

The attaching pins 9 are adapted to cooperate with

2

rectangular openings 11 in a sheet 10 to be filed, see particularly FIG. 7 so that the sheets may be disposed in hanging relationship to individual threads as is shown most clearly in FIG. 3.

5 As can be seen best in FIGS. 4 and 5, the height of each opening 11 is greater than the distance between a thread 8 and the upper end of the pins 9 while, at the same time, it can be seen that the lower end of each pin 9 is of greater length than its upper end. Thus, to engage a sheet 10 upon an individual thread, the openings 11 are manipulated to first receive the lower portion of the pins 9 as shown in FIG. 4 whereafter the sheet may be swung over to clear the upper end of each pin in a fashion shown in FIG. 5 such that when the sheet is 15 then moved downwardly, a positive attaching operation is effected. At the same time it will be appreciated that the lower portion of each pin is sufficiently long as to preclude accidental disengagement of a sheet from its pins.

20 In order to facilitate identification of the sheet so filed, an indicating or identifying card 12, FIG. 8, may be provided. This card is provided with V-shaped slits 13 and opposite edge intersecting slits 14 substantially as shown so that the card may be engaged on a thread in a fashion indicated in FIG. 6.

25 Although certain specific embodiments of the invention have been shown and described, it is obvious that many modifications thereof are possible. The invention, therefore, is not to be restricted except insofar as it is necessitated by the prior art and by the spirit of the appended claims.

I claim:

1. A file assembly comprising, in combination, a framework including a pair of bars disposed in horizontally spaced relation and means for selectively varying the spacing between the bars, a plurality of thread members extending horizontally between and supported by said bars, a plurality of pin members carried by each thread member, each pin member having an upper part projecting above its associated thread member and a lower part depending from its associated thread member, each such lower part being of greater length than the upper part, and a file sheet having a pair of spaced openings along its upper edge, each opening being of a height dimension that is greater than the length of said upper parts of the pin members but is less than the length of said lower parts of the pin members, the pin members on one of said thread members being passed through said openings to secure the file sheet in suspended relation to such one thread member.

2. The file assembly as defined in claim 1 wherein a generally C-shaped ring secures each end of each thread member to said bars.

3. The file assembly as defined in claim 1 including an identification card having a pair of horizontally spaced V-shaped slits and opposite side slits receiving one of said thread members and attaching the card thereto.
